UNITED STATES PATENT OFFICE.

ALFRED F. McCOLLUM, OF BLOOMSBURG, PENNSYLVANIA, ASSIGNOR TO THE MAGEE CARPET COMPANY, OF BLOOMSBURG, PENNSYLVANIA, A CORPORATION OF PENNSYLVANIA.

RUG.

Application filed May 17, 1924. Serial No. 714,000.

To all whom it may concern:

Be it known that I, ALFRED F. McCOLLUM, a citizen of the United States, residing in Bloomsburg, Columbia County, Pennsylvania, have invented certain Improvements in Rugs, of which the following is a specification.

The object of my invention is to construct a rug so that the corners will be prevented from curling up.

This object I attain by reinforcing the corners with a flexible material that will retain the corners of the rug in a flat position at all times.

15 In the accompanying drawings:

Fig. 1 is a plan view of a rug showing my improved corner reinforcing means in dotted lines;

Fig. 2 is a plan view of one corner of a rug showing the fringe and heading broken away to expose the reinforce;

Fig. 3 is a sectional view on the line 3—3, Fig. 2;

Fig. 4 is a fragmentary perspective view illustrating the invention; and

Fig. 5 is a detached perspective view of the flexible reinforce.

Referring to the drawings, 1 is the body of the rug, which may be of any weave. 20 2 is the binding at the end of the rug, enclosed by a heading 3 of a fringe 4. A flexible strip 5 of reinforcing material is located at the four corners of the rug, as shown clearly in Fig. 1. This flexible strip may 25 be of feather bone, whalebone, &c., but must have sufficient elasticity to retain the corners of the rug flat on the floor.

In Fig. 5, a flexible material, known as

“feather bone”, is illustrated. This material has a certain amount of flexibility, yet will 40 retain the corners of a rug, in which it is inserted, in a flat condition.

While it is preferred to employ a short strip at each corner of a rug, a strip of greater length may be used, depending upon 45 the size and character of the rug.

In some types of rugs, the fringe is omitted, in which case, the reinforce is enclosed within the binding. While the reinforce is shown on the upper surface of the 50 ends of a rug, outside of the pile, it may be located at the corners on the underside of a rug, without departing from the essential features of the invention.

I claim:

1. The combination in a rug body, of short sections of flexible, reinforcing strips at the corners thereof; and a binder for the raw edges of the rug, said binder enclosing the 55 flexible, reinforcing strips.

2. The combination in the body of a rug, of short sections of flexible, reinforcing strips at the corners thereof; a binder at each end of the rug binding the raw edges thereof and engaging the flexible strips; and a fringe at each end of the rug having 60 a heading extending over the binder and the flexible, reinforcing strips.

3. The combination of the body portion of a rug having a pile; strips of flexible material at the corners of the rug beyond the pile; a binder for the raw edges of the rug beyond the pile, said binder enclosing the flexible strips; and a fringe having a heading 65 extending over the binder.

ALFRED F. McCOLLUM.
